UNITED STATES PATENT OFFICE.

GEDOR W. ALDEEN, OF ROCKFORD, ILLINOIS, ASSIGNOR TO NATIONAL LOCK CO., OF ROCKFORD, ILLINOIS, A CORPORATION OF DELAWARE.

HINGE.

Application filed June 23, 1924. Serial No. 721,626.

This invention relates to improvements in hinges generally, although more particularly to hinges adapted for use in connection with refrigerator doors.

5 Heretofore, it has been the practise to construct these hinges from sheet metal and to form one of the leaves with an upwardly extending flange which is formed into bearing eyes for the pintle. The metal at the 10 juncture or bend between the flange and the body portion of the hinge leaf is necessarily weak and is subject to severe strains which result in the flange being ruptured from the body portion.

15 The principal object of my invention is, therefore, to provide a hinge leaf formed of sheet metal and constructed in a manner to sufficiently re-inforce the juncture between the flange and the body portion 20 whereby a rupture of that juncture will be prevented.

Another object of the invention is to provide a novel method of producing such a hinge section from sheet metal.

25 In the accompanying drawings which show my improved hinge and the method of forming same,

Figure 1 is a plan view of a stamped blank (which has been cut to form) and the 30 first step in the method of producing said leaf,

Figure 2 is a detail plan view showing the second step in the method, the intermediate tongue being rolled to form an intermediate bearing,

35 Figure 3 is a plan view showing the third step in my method, the blank being properly shaped,

Figure 4 is a top plan view illustrating the next step in the method, the marginal side portions, together with the outer bearing arms being bent downwardly at right angles to the body portion,

40 Figure 5 is a side elevation of the leaf shown in Figure 4,

Figure 6 is a longitudinal sectional view showing the last step in my improved method and illustrating the completed leaf,

Figure 7 is a plan view of the blank from 50 which the other leaf of the hinge is formed,

Figure 8 is a plan view showing the marginal side portions of said blank folded to form a depending re-inforcing flange,

55 Figure 9 is a longitudinal sectional view taken on the line 9—9 of Figure 8, and,

Figure 10 is a side elevation of a hinge constructed in accordance with my invention.

My invention is directed to a hinge which is adapted especially for use in connection with refrigerator doors and this hinge includes pivotally connected leaves A and B which are formed from sheet metal.

In forming the leaf A I stamp or otherwise cut a blank 5 from sheet metal stock so as to form a body portion 6 and a plurality of outer tongues 7—7 and an intermediate tongue 8, all of said tongues projecting in the same general direction from one end of the body portion. The intermediate tongue 8 is spaced equidistant from the outer tongues 7—7 and extends beyond the ends of said tongues for an appreciable distance. The body portion 6 is punched to form openings 9 for receiving attaching screws and the tongues 7—7 are respectively punched 75 to provide bearing openings 10—10.

After the blank has thus been formed, the intermediate tongue 8 is then rolled to form an intermediate bearing 11, as shown in Figure 2.

The blank is then shaped to the contour shown in Figure 3, thereby forming the tongues 7—7 into bearing arms 12—12 which extend from the marginal side portions of the body portion and have their longitudinal axes disposed at approximately 90° to each other.

The article as thus formed is then subjected to a pressing operation which results in bending the marginal side portions downwardly, together with the bearing arms 12, into a plane at substantially right angles to the plane of the body portion into position shown in Figures 4 and 5 on the drawing, this operation forming resultant re-inforcing flanges 13 for the body portion, and causing the bearing arms 12 to be projected above the plane of the body portion.

Simultaneously with this pressing operation the screw holes 9 are depressed to receive the heads of the attaching screws.

It is desired to project the bearings above the plane of the body portion, and also to straighten the lower edge of the bent over marginal portions whereby the leaf will set 105 firmly against its support. The leaf is therefore subjected to a swaging operation which raises the hinge end of the leaf and simultaneously straightens the lower edge of the bent over marginal portions as shown in 110

Figure 6. This swaging operation positions the bearing openings 10-10 above the plane of the body portion. The intermediate bearing 11 is, of course, raised into alignment with the bearing openings 10-10, and this aligning of the intermediate bearing is preferably accomplished during the swaging operation.

Thus, the body portion 6 of the leaf is formed with an upwardly extending flange 14, and as a result, the juncture between the body portion 6 and the flange 14 is re-inforced by the integral bearing arms 12-12 to such an extent that strains imparted to the hinge will neither rupture nor distort said juncture.

The hinge section B is formed from a sheet metal blank 15 which is cut to provide a pair of bearing tongues 16-16 which project in the same general direction from one end of the body portion. The tongues 16 are subsequently rolled to form aligned bearings 17-17 which are adapted to fit between the outer bearing arms 12-12 and the intermediate bearing 11 of the leaf A, all of said bearings being connected by the usual pintle 18. The blank 15 is formed with a plurality of screw openings 19, and the marginal portions of the blank are bent downwardly to form a marginal flange 20.

From the foregoing, it will be observed that I have provided the hinge leaf A with spaced outer bearings which are formed in bearing arms extending from and forming a continuation of the marginal down turned side portions of the body portion; that the bearing arms are integral with and brace the upwardly extending flange, and as a result the juncture between the body portion and said flange is sufficiently re-inforced to prevent rupture or distortion thereof.

I claim:

1. A hinge section formed from sheet metal bent to form a body portion having one end thereof bent upwardly to form a flange, the marginal side portions of the body portion being bent downwardly to form reinforcing flanges, said reinforcing flanges respectively extending forwardly beyond the upwardly extending flange and having integral connection therewith to reinforce the juncture between the body portion and the upwardly extending flange, said forwardly projecting flange portions being respectively formed with bearing openings

disposed in a plane above the plane of the body portion, and a rolled bearing formed integrally with said upwardly extending flange and disposed intermediate said bearing openings and in alignment therewith. 60

2. In a door hinge, a pair of pintle-connected leaves secured to the door members respectively, one of the leaves having a body portion disposed parallel with the door member to which it is secured and a portion 65 extending outwardly from said door member and provided with flanges at its side edges extending toward the other door member.

3. In a door hinge, a pair of pintle-connected leaves secured to the door members respectively and provided with flanges at their side edges and free-end edges extending inwardly toward the door members respectively, one of the leaves having a portion 75 extending outwardly from the door member to which it is secured and provided with flanges at its side edges continuous with its said side-edge flanges and extending toward the other door member. 80

4. A hinge section formed from sheet metal bent to form a body portion having downwardly extending marginal side flanges, said flanges extending beyond one end of said body portion and provided with 85 aligned bearing openings respectively.

5. A hinge section formed from sheet metal bent to form a body portion having depending marginal side flanges, said flanges extending beyond one end of said body portion to form substantially flat bearing arms 90 lying in parallel planes respectively and normal to the body portion.

6. A hinge section formed from sheet metal bent to form a body portion having 95 downwardly extending marginal side flanges, said flanges extending beyond and above one end of said body portion and provided with aligned bearing openings respectively. 100

7. A hinge section formed from sheet metal bent to form a body portion having downwardly extending marginal side flanges, said flanges extending beyond one end of said body portion and a bearing disposed on said body portion intermediate such extensions of the flanges, the extensions provided with bearing openings in alignment with said bearing. 105

GEDOR W. ALDEEN.
